Primary Examiner — Ricky Pham(74) *Attorney, Agent, or Firm* — Lowe Graham Jones PLLC(57) **CLAIM**

I claim the ornamental design for the salad spinner lid, as shown and described.

DESCRIPTION

FIG. 1 is a top perspective view of a salad spinner lid, showing my new design.

FIG. 2 is a top plan view of the salad spinner lid.

FIG. 3 is a left side view of the salad spinner lid, the right side view being a mirror image.

FIG. 4 is a front view of the salad spinner lid, the back view being a mirror image; and,

FIG. 5 is a bottom view of the salad spinner lid.

Components shown in broken lines are for illustrative purposes only and form no part of the claimed invention.

1 Claim, 4 Drawing Sheets(56)
